UNITED STATES PATENT OFFICE.

JOHN I. McCORMICK, OF CHICAGO, ILLINOIS, ASSIGNOR TO AMERICAN SLICING MACHINE COMPANY, OF CHICAGO, ILLINOIS, A CORPORATION OF ILLINOIS.

MEAT-SLICER.

1,142,901.

Specification of Letters Patent. Patented June 15, 1915.

Application filed March 24, 1911. Serial No. 616,586.

To all whom it may concern:

Be it known that I, JOHN I. McCORMICK, a citizen of the United States, residing at Chicago, in the county of Cook and State of Illinois, have invented a certain new and useful Improvement in Meat-Slicers, of which the following is a specification.

My invention relates to improvements in meat slicers and is illustrated diagrammatically in one form in the accompanying drawing, wherein—

Figure 1 is a side elevation of a machine with the device applied thereto; Fig. 2, a section along the line 2—2 of Fig. 1; Fig. 3, a section along the line 3—3 of Fig. 1.

Like parts are indicated by like letters throughout the several figures.

The closed base A, from which projects the upwardly extending column or box A¹, is provided with the tracks A², upon which is mounted the reciprocating meat carriage A³, in opposition to the rotating knife on the shaft A⁵, mounted in the box A¹. The carriage A³ is reciprocated and the knife rotated by means of mechanism within the base A, which is operated by the shaft A⁶ and fly wheel A⁷.

B is a rotary disk-shaped knife which has the beveled edge B¹, the inner beveled surface B² and the groove B³ intermediate the surfaces B¹, B².

C is a curved deflector or scraper associated with the guard rail D from which latter inwardly projects two arms D¹, D¹, shaped as shown. Each is slotted at D² to receive one end of the deflector C, and each end is held in position by means of the thumb screw D³. The inner ends of the arms D¹ pass through apertures in the spacing rod E and are held in position by the set screws E¹, E¹ in the end of such rod. This rod has an inwardly projecting arm E² pivoted at E³ to the bracket E⁴.

F, F, are springs attached each at one end by the set screws F¹, F¹ to the spacing rod and at the other end to a pin F² mounted in the bracket back of the pivot point E³ and above the same. On the inner end of the arm E² is a notch G adapted to receive the dog G¹ which is secured to the bracket by means of the slot G² and screw G³.

When the parts are in the position shown in full lines in Fig. 2, the guard is slightly in advance of and back of the rotating knife, the deflector is in the groove of the knife 55 and pressed thereagainst by the springs F, F. Its motion in that direction is adjustably limited by the dog G¹ which can be set in position by means of the screw G³ in the slot G². In this position, the knife and its 60 guard and deflector are ready for use.

In the position shown in dotted lines, the movable guard and deflector,—and in this form of the device they are associated together—are thrown outwardly so as to leave 65 the knife edge free for grinding or cleaning, and they are held in this position by the spiral springs F because the engagement of the springs with the bracket at the pin F² is back of and above the pivot point of the 70 guard and deflector.

The use and operation of my invention are as follows: In operating the slicer, with my device attached, the knife slices the meat in the usual manner, except that the deflector 75 guides the meat and grease outwardly away from the surface of the knife, thus preventing the lodgment of grease and heat particles upon the body of the knife. The deflector being in engagement with the shoulder or groove at the rear of the cutting edge, effectively prevents the deposit of any foreign substance, such as small meat particles or grease upon the body of the blade and keeps it in a clean and sanitary condition. 80 The fact that the edge of the deflector blade is located within the groove in the cutting surface obviates the need of any very close adjustment of the deflector and makes it possible to set the deflector in a predetermined position without making it necessary to compensate for irregularities in the knife. The deflector is held in position by the spiral springs which draw the lug on the supporting arm over against the adjustable dog on 95 the supporting bracket. It will be evident that by adjusting this dog the position of the deflector may be varied to suit any style or thickness of knife. It will also be observed that the deflector strip may be adjusted for different sizes of knife, in view of 100 the fact that it is slidably held at either end

in the supporting brackets. The guard, which is carried by the supporting arms, is partially removed from the cutting edge to permit the knife to operate, but at the same time is sufficiently close thereto to protect the edge from contact with the clothing or fingers of the operator.

I claim:

1. A meat slicer comprising a rotary cutting knife and an adjustable normally fixed blade in contact therewith, located adjacent and substantially concentric with the cutting edge and interposed between it and the center of the knife.
- 10 2. A meat slicer comprising a rotary recessed cutting knife and an adjustable normally fixed blade in contact with said knife and in engagement with the recess therein.
- 15 3. A deflector for meat slicing machines, comprising a bracket, an arm pivotally mounted thereon, a spacing rod carried by said arm, arms adjustably mounted upon said rod and a deflecting blade adjustably mounted upon said arms in contact with the knife.
- 20 4. A deflector for meat slicing machines, comprising a bracket, an arm pivotally mounted thereon, a spacing rod carried by said arm, arms adjustably mounted upon said rod and a deflecting blade adjustably mounted upon said arms in opposition to the knife, elastic means for holding said blade in contact with said knife.
- 25 5. A deflector for meat slicing machines comprising a bracket, an arm pivotally mounted thereon, a spacing rod carried by said arm, arms adjustably mounted upon said rod and a deflecting blade adjustably mounted upon said arms in opposition to the knife, elastic means for holding said blade in contact with said knife.
- 30 6. A meat slicer containing a rotary grooved knife and an adjustable and movable deflecting blade within said groove.
- 35 7. A flexible curved deflecting blade for slicing machines and means for varying the radius of curvature of said blade.
- 40 8. A flexible curved deflecting blade for slicing machines and means for varying the radius of curvature of said blade, said means comprising supporting arms in which the ends of said blade are carried and means for adjusting said ends within said arms.
- 45 9. The combination with a meat slicing machine of a pivotally mounted guard for the effective cutting portion of the knife and means for swinging said guard out of the plane of the knife, said guard being substantially concentric with the knife and located in a plane parallel to it.
- 50 10. The combination with a meat slicing machine of an arm pivotally mounted thereon, a deflector adjustably mounted upon said

bracket and means for bringing said deflector in contact with the surface of the knife and adjustable means for limiting the movement of said deflector in the direction of the knife.

11. A meat slicer comprising a rotary cutting knife, an adjustable normally fixed deflecting blade adjacent thereto and immediately back of the cutting edge, means for locking said blade in position adjacent the knife and means for locking it in position removed from the knife.

12. A meat slicer comprising a rotary cutting knife, a pivotally mounted deflecting blade adjacent thereto, means for holding said blade in position adjacent the knife, said blade being adapted to be moved away from the knife and means for holding it away from the knife.

13. A meat slicer comprising a rotary cutting knife, a pivotally mounted deflecting blade adjacent thereto located between the cutting edge and the axis of rotation, said blade being normally fixed in position but free to swing away from the knife and yielding means for locking it in position.

14. A meat slicer comprising a rotary recessed cutting knife, and an adjustable blade normally fixed in position and located within said recess but out of contact with the knife.

15. A meat slicer comprising a rotary cutting knife, a deflector in opposition thereto pivotally mounted to swing to and from the knife and means for yieldingly holding said deflector in position adjacent the knife and away from the knife.

16. A meat slicer comprising a rotary cutting knife, a deflector in opposition thereto pivotally mounted to swing to and from the knife and means for yieldingly holding said deflector in position adjacent the knife and away from the knife, the edge of said deflector being slightly removed from the cutting edge of the knife and located between it and the center of rotation of the knife.

17. The combination with a meat slicing machine of a guard for the effective cutting portion of the knife comprising a curved member substantially concentric with and curved about a slightly larger radius than the knife, a support upon which the bar is adjustably mounted, said support being pivoted for rotation on an axis perpendicular to the axis of rotation of the knife and means for holding said guard in position in a plane slightly behind the plane occupied by the cutting edge of the knife and parallel with such plane.

18. The combination with a meat slicing machine of a guard for the effective cutting portion of the knife comprising a curved member substantially concentric with and curved about a slightly larger radius than

the knife, a support upon which the bar is adjustably mounted, said support being pivoted for rotation on an axis perpendicular to the axis of rotation of the knife and 5 means for holding said guard in position in a plane slightly behind the plane occupied by the cutting edge of the knife and paral-

lel with such plane, the pivotal point of said support being located adjacent the axis of rotation of the knife.
